[57] CLAIM

The ornamental design for a vertically-mountable ticket
dispenser, as shown and described.

DESCRIPTION

FIG. 1 is a front elevational view of a vertically-mount-
able ticket dispenser showing our new design;

FIG. 2 is a rear elevational view;

FIG. 3 is a bottom plan view;

FIG. 4 is a top plan view;

FIG. 5 is a left side elevational view, the right side being
a mirror image thereof; and,

FIG. 6 is a top, right front perspective view thereof.

*FIG. 1**FIG. 3*FIG. 2

FIG. 4

FIG. 6
